HOLE BORING MACHINE

George H. Connors, Edgerton, Wis., assignor to
Highway Trailer Company, Edgerton, Wis., a
corporation

Application April 16, 1948, Serial No. 21,389

8 Claims. (Cl. 255—22)

1

My present invention embodies improvements in earth hole boring machines of the general type depicted in United States patent of Erdahl, No. 1,921,812, dated August 8, 1933, and Spowart Patents 1,511,433, dated October 14, 1924, and 1,531,266, dated March 24, 1925.

The improvements made by me include provisions such that the customary boring bar or shaft carrying the boring auger may perform its hole digging function by gravity feed action depending on the weight thereof while being rotated; other provisions that may be brought into play involving certain positive ratchet feed mechanism for operating the auger should the gravitation of the auger and boring bar be insufficient to dig in high resistance earth formations; and still other provisions, including fluid pressure operated means to supplement the action of the positive ratchet feed instrumentalities, or work independently of the latter, for causing the boring operation of the auger.

Other special features of my invention include novel operating mechanism to effect feed reversal of the auger to raise the same from the bored hole, under ordinary conditions of use, without varying the operation of the input power driving means of the auger, and when such action involves special difficulty, other control mechanism that may be used with which to compel such auger withdrawal operation.

My invention involves additional novel detail features of construction and operation of my boring unit, all of which will later be set forth fully herein.

In the accompanying drawings forming a part of my application, the several figures are described as follows:

Figure 1 is a side view looking toward the rear end portion of a truck upon which the boring mechanism of my invention is mounted.

Figure 2 is a rear elevation showing very largely the same structure as is depicted in Figure 1, certain of the rear wheels of the truck omitted and the chassis broken away.

Figure 3 is a transverse vertical sectional view taken largely through the boring head and enclosed gear mechanism and auger rack and through the intermediate gear housing located at one side of the boring head.

Figure 4 is a fragmentary sectional view showing more clearly the upper end of the auger moving rack bar, and illustrating the piston carried by said upper end and operating in the guide pipe which is mounted to extend upwardly from the boring head.

Figure 5 is a view somewhat similar to Figure 1, with the parts enlarged, showing the main supporting housing for the boring mechanism, same carried by the chassis of the truck on which the unit is mounted, the clutch and brake casing

or housing portion of the supporting housing being broken away to show the clutch and brake features in section; also the intermediate housing associated with the boring head being broken away to show the arrangement of the driving shaft at its front end, and the driving gear carried thereby.

Figure 6 is an enlarged view broken away, showing more particularly the boring head, said head having the housing portion thereof broken away to show the intermittently operated pawl lever and toothed ratchet wheel engageable by the pawls of said lever; also some other details are shown in this view, including a portion of the brake lever and a portion of the trip pin and actuating lever for the latter, said pin in upraised condition.

Figure 7 is a horizontal sectional view through the rotating carrier for the rack bar of the auger, the view being taken about on the line 7—7 of Figure 8.

Figure 8 is a view largely in elevation, showing the carrier unit alone and bringing out more clearly the mounting of the trip lever for the ratchet pawls, the associated ratchet wheel, and the brake drum unit which forms a part of said carrier unit in that the brake drum unit is associated with said carrier unit.

Figure 9 is a view similar to Figure 8, looking at the carrier unit from a direction opposite to that seen in the view Figure 8, bringing out more clearly the mounting of certain gears which are supported on the carrier unit to rotate bodily therewith and with the rack bar, the lower portion of the carrier unit being broken away.

Figure 10 is a vertical sectional view taken about on the line 10—10 of Figure 8 and bringing out more clearly the mounting means for the ratchet lever, and certain detent means cooperating with the springs by which the ratchet lever is maintained normally in a certain position.

Figure 11 is a fragmentary view showing a modified arrangement of one of the gears of the drive gearing.

Describing my invention specifically, reference is had primarily to Figures 1, 2, and 5 of the drawings hereto annexed. As seen in these figures, my boring mechanism comprises a unit which is adapted to be mounted upon the rear end of the chassis 1 of a suitable power driven truck, or tractor, rear wheels 2 of which are shown. My boring unit is suitably supported on the truck chassis 1 by cross beams 3, and comprises essentially a main support housing 4 at the inner end of which is mounted an input shaft 5 having the exposed drive pinion 6 meshing with a gear 7 on a power take-off shaft 8 which is adapted to be connected with a power take off unit associated with the transmission of the truck

or automobile chassis by which my boring mechanism is carried. The input shaft 5 is adapted to be connected to a longitudinal drive shaft 9 within the support housing 4 by means of a clutch 10 of the multiple disc type, the discs of which are adapted to be actuated by a throw collar 11 on the shaft 9 shiftable by means of the yoke 12 on a transverse shifting shaft 13. Shaft 13 is adapted to be rocked by an arm 14 connected by link 15 with the bell crank lever 16 operable by an actuating link rod shown in dotted lines in Figure 1 at 17 movable longitudinally by an operating arm 18 on the hand lever 19 which is located adjacent to the auger 20 of my boring mechanism.

The clutch shifting collar 11 also cooperates with brake means comprising multiple discs 21 coacting with the shaft 9 through the provision of the clutch and brake hub 22 connected to said shaft 9, and in the operation of the hand lever 19 application of the clutch means 10 is effected incident to release of the brake means 21, and application of the brake means 21 will simultaneously effect a release action of the clutch means 10. In the above manner, by use of the lever 19, power is transmitted from the input shaft 5 to the driving shaft 9 by rendering the clutch means 10 operative, and discontinuance of the drive on the shaft 9 is effected by release of the clutch means 10. Stopping of the shaft movement of shaft 9 may be effected, of course, by the brake means 21, and the normal position of the shift member or yoke 12 is at neutral, which involves a corresponding maintenance of the hand lever 19 in neutral position.

The driving shaft 9 of my boring unit extends at its outer end into an intermediate gear housing or case 23 having rotatable mounting connection seen at 24 in Figure 5, between said gear case and the support housing 4. On its outer end and within the gear case 23 shaft 9 carries the driving bevel pinion 25 which pinion is adapted to mesh with a removable and adjustable driving bevel gear 26 keyed to an auxiliary driving shaft 27 arranged in suitable bearings and disposed transversely relatively to the shaft 9, within the gear case 23, see Figure 3. By the provision of a removable door and bearing plate 28 on the free outer end of the gear case 23, the gear 26 carried by the shaft 27 may be readily reversed from the position in which it is shown in Figure 3, to the position illustrated in Figure 11, so that the gear 25 on the shaft 9 may drive the shaft 27 in reverse directions, depending upon the emplacement of the gear 26 in connected relation to the shaft 27 in either position shown in Figure 3 or that shown in Fig. 11. The purpose of this reversible mounting adaptability of the gear 26 will appear later herein.

Associated with the intermediate gear case 23 at the end thereof opposite the removable door plate 28 is the boring head or housing of my boring unit, the same designated 29 and shown best in Figures 3, 5, and 6 of my drawings. The boring head 29 is hollow and therefore forms a housing for certain mechanism of my boring unit. It is mounted in a rotatable manner upon the adjacent end of the intermediate casing 23 by the rotative connecting portions of the head 29 located at 30, see Figure 3, the axis of the rotative connection 30 being concentric with the axis of the auxiliary drive shaft 27, just as the rotative connection 24 between the stationary supporting housing 4 and the intermediate gear

case 23 is located such that its axis is concentric with the shaft 9.

In a general manner the above relation of the mountings of the gear case 23 on the supporting housing 4 and the mounting of the boring head 29 containing certain of the boring mechanism upon the intermediate gear case 23 are features of the present machine quite well known in the art as disclosed in prior patents of Spowart, No. 1,511,433, dated October 14, 1924, and Erdahl, No. 1,921,812, dated August 8, 1933, upon which type boring machine construction my present invention improves. The purpose in the relative mountings of the support housing 4, intermediate casing 23, and the boring head or housing 29, is to deal with conditions of actual use of the auger boring instrumentality 20. In boring holes, the surface of the ground immediately adjacent the place where the hole is to be dug is sometimes sloping, and the supporting vehicle or machine for my boring unit cannot readily be properly positioned for making a vertical boring. Under these conditions the entire boring head with its auger is made adjustable about a pair of horizontal axes disposed transversely of each other to provide universal adjustment of the auger 20. One of these axes is the longitudinal axis of the support casing 4 and the shaft 9, and the other axis is the axis, practically speaking, of the intermediate casing 23 comprising the shaft 27 about which the rotative connecting features of construction, designated 30, are disposed. The above adjustments also permit of boring holes at an angle when the occasion necessitates. The adjustment is made about an axis extending longitudinally of the machine and notably the axis of the housing 4 when the boring auger 20 is to be disposed at an angle lateral to the longitudinal axis of the machine, and the adjustment of the boring head 29 for the above purpose is effected by the use of the segment 31 attached to the rear portion of the intermediate casing 23, operable by a worm 32 having a square ended shaft for application of a turning handle thereto. After a known manner, the boring head 29 at its side adjacent to the intermediate casing 23 is equipped with a worm segment 33 engageable by a worm 34 carried by the intermediate case 23 and also having a square ended turning shaft for application of a suitable handle for turning, whereby to adjust the boring head in forwardly and rearwardly extending directions at a desired vertical angle in a plane longitudinally of the vehicle or machine on which the boring mechanism is mounted. As previously indicated, the foregoing features of relative adjustment of the boring head about a pair of horizontal axes disposed transversely to each other is known to the art, especially by reference to the Erdahl patent previously referred to, and forms no special feature of the present invention.

The auger 20 is supported by a boring bar or shaft 35, the cross section of which is preferably square, see Figure 7, and at one side of said bar are provided teeth 36 forming a rack.

My boring bar 35 extends vertically through the boring head 29 and is directly received in a rotary carrier disposed in said boring head and comprising largely the vertical tubular body casting or body 37 through which the bar 35 passes, said carrier body 37 having at its upper end a thrust plate cage 38 supporting the thrust plates 39, and also having a similar arrangement at the lower end thereof comprising the plate cage 40 and the

thrust plates 41. On a middle approximately horizontal flange 42 surrounding the carrier body 37 is secured a carrier driving ring gear 43 of the bevel type. This gear is fixed to the carrier flange 42 and the teeth of the gear mesh with those of the driving pinion 44 and which is suitably keyed to the reduced inner end of the auxiliary driving shaft 27 in the gear case 23. The thrust plates 39 and 41 in the body 37 of the carrier provide virtually square sockets in which the square cross section body of the boring bar 35 is snugly received, and held so that the boring bar may freely slide longitudinally of the carrier 37. Owing to this constructional feature of the receiving means on the carrier 37, for the boring bar 35, it is evident that as the carrier 37 is rotated by the driving action of the auxiliary shaft 27 and the meshing gears 44 and 43, the boring bar 35 will be correspondingly rotated and this rotation should be in a clockwise direction by reason of the nature of the pitch of the screw portion of the auger 20 which penetrates the ground or earth incident to the rightwise or clockwise rotation of the auger. Under these conditions, therefore, the drive of the carrier 37 must always be in a clockwise direction looking downwardly on the boring unit, irrespective of the direction of the drive taken off from the transmission of the vehicle which carries the boring unit. The proper direction of rotation of the auger shaft or bar 35 may readily be maintained, as derived from the shaft 9, the latter being turned in one direction or the other by reason of the adaptability of the gear 26 to be placed in either the position shown in Figure 3 or that shown in Figure 11, in respect to the gear 25 of the shaft 9. The purpose of the reversible arrangement of gear 26, as previously mentioned, is thus explained.

Now according to the improvements of my present invention, it is contemplated that the boring bar 35 shall be adapted to gravitate downwardly in and through the carrier 37 under normal conditions of boring operations. It is deemed sufficient, under such conditions, to rely upon considerable weight of the auger 20 and that of the boring bar 35 to cause the earth penetration of the auger 20 under usual conditions of digging.

In view of the last foregoing mode of functioning of my present invention I am enabled to eliminate certain of the drive gearing that is employed in machines of the type of my invention as disclosed in the Spowart and Erdahl patents referred to, by which gearing down feeding of the auger into the earth is produced, also certain gearing employed in standard type clutches used in prior machines of said earlier type need not be employed.

According to my present invention, instead of employing the continuous operating speed gearing heretofore generally used for the operation of the boring bar 35 in its boring action, I employ certain speed gear means for the boring bar also cooperating with the rack teeth 36 of the latter, but susceptible of being intermittently operated at the will of the operator of the machine, when and if digging power supplemental to that of the weight of the boring bar and the auger is found necessary to be employed. With the foregoing in view, my intermittently and manually controlled means for applying digging effort to the auger contemplates the employment of certain ratchet feeding mechanism shortly to be described.

In addition to the feature of the supplemental positive ratchet feed mechanism referred to

above, it is known that at times, when obstacles are met with in the earth in which the bore hole is being made, very powerful digging drive of the auger is required to be resorted to. With this in mind, therefore, for digging in hard or frozen ground, or when digging at an angle when the force of gravity of the auger and the boring bar is not sufficient, the auxiliary ratchet feeding means may be employed and additional thereto I utilize a hydraulic type of feed control, or I may use either one of these types of feeds dependent upon the conditions met with and at the will of the operator in his discretion.

I first refer to the hydraulic means just mentioned, and note, as seen in Figures 1 and 4 of my drawings particularly, that I utilize the customarily employed guide type or tube 45 projecting upwardly from and secured to the boring head 29, as a piston tube, the same receiving the piston 46, see Figure 4, affixed to the top end of the boring bar 35 so that when hydraulic or other fluid pressure is admitted to the upper end of the guide tube 45 and applied to the upper surface of the piston 46, the piston and boring bar 35 will be subjected to the pressure of said fluid to force the auger 20 into the earth being bored. In this manner, by using the fluid pressure on the piston 46, I may apply a supplemental digging force to the auger 20 additional to the gravitational force generated by the weight of the auger and said boring bar. In Figure 1 of the drawings, the conduit 47 which supplies the pressure fluid to the upper end of the guide and piston tube 45 is shown, but since hydraulic or pressure fluid supply means for such conduit 47 may be of any known types, including the necessary pump valve, reservoir, and conduit connections, the latter are not shown and described, being no part of my present invention.

I now refer to my intermittently usable and preferably ratchet feed type feeding instrumentalities for positively feeding the auger 20 to its work when recourse to such supplemental feeding means is desirable.

On the upper portion of the boring head 29, designated 29a, is mounted for vertical sliding movement a trip pin 48 normally upraised by means of a spring 49. At its upper end the trip pin is connected pivotally at 50 with an operating lever 51 located conveniently to the operator of the boring unit when in use, he usually standing near the rear end of the truck and at one side of said unit. The lower end of the trip pin 48 enters the housing of the boring head 29 and may be moved downwardly variable distances dependent upon the pressure on the hand lever 51, in order to engage with the upper end of a trip or ratchet lever 52 which is supported on a pivot shaft 53 mounted in bearing portions 54 constituting integral parts of the carrier 37. The ratchet lever 52 supports above its pivot shaft 53 a pawl 55 having an end thereof adapted to engage a ratchet wheel 56 on a counter shaft 57 which is parallel with the pivot shaft 53. The ratchet wheel 56 is keyed to the shaft 57 and the latter is mounted in suitable bearings of an extension 58 projecting from the carrier 37. On its end opposite that carrying the ratchet wheel 56 the shaft 57 supports a spur pinion 59 which meshes with a similar spur pinion 60 on another shaft 61 supported in suitable bearing means and also carried by the carrier 37. The spur pinion or gear 60 is an integral part of a combination spur gear and bevel pinion unit which comprises the bevel pinion 62

arranged at the outer side and connected with the hub portion of the pinion 60.

Below the pawl 55 and mounted also on a pivot shaft 64 carried by the lower end of the ratchet lever 52 is a second feed pawl 65, one end of which is also adapted to engage the ratchet wheel 56 upon rocking of the lever 50 to turn the wheel 56 in a direction opposite to that in which it is turned by the ratchet pawl 55.

Between the tails of the pawls 55 and 65 is interposed a spring 66a normally expansible to hold the pawls in predetermined normal positions as fixed by means of set screws 67 supported on a suitable boss 68 adjacent to the axis shaft 53 of the lever 52. The pivot shaft on the lever 52 provided for the pawl 55 is designated 64a and is similar to the shaft 64 except in one respect now to be pointed out. The outer end of the shaft 64 for the pawl 65 is formed with a head having a depression therein, shown in Figure 10, and a hollow detent pin 66 is adapted to enter said depression for the purpose of generally maintaining, by its detent action, the lever 52 in a normal vertical position. The lever 52 is assisted in maintaining such position by having coil springs 67a connected at their outer ends to posts 68a and connected at their inner ends to opposite sides of the lower end of the lever 52 as shown clearly in Figure 8, in which the outer bearing boss for the lever pivot shaft 53 is omitted in order to clarify this illustration.

As seen in Figure 10 the body portion of the lever 52 is of considerable width to provide an in-bearing member 69 that is vertically parallel with the out-bearing body portion of the lever 52, the parts 69 having the bearings for the inner ends of the pivot shafts 64 and 64a of the pawls 65 and 55, respectively. The detent pin 66 is held in place by a screw plug 70, and the spring 71, pressing on the detent 66 causes cooperation of the detent 66 with the lever since the normal tendency of the detent is to seek its true central seat in the end of the pin or pivot member 64 to overcome any slight difference that may be present in the tension of the respective two springs 67 used for centralizing the lever 52 in its vertical normal position.

With the construction of the last described means in mind, it is obvious that as the carrier 37 is rotated by the driving action of the auxiliary driving pinion 44 engaging the ring gear 43, should the operator desire to bring into action the supplemental ratchet feed means for the boring bar 35 and its auger 20, the trip pin 48 may be pressed downwardly by means of the lever 51 so as to have its lower end projected into the path of the upper end of the lever 52. Assuming that the carrier 37 is rotating in the direction of the arrow A shown on Figure 8 as the ratchet lever 52 is carried around rotatively with the carrier, it will be struck or tripped by the trip pin 48 hitting the said upper end of the lever 52 on its left side to rock the lever 52 on its pivot shaft 53 each time the lever 52 is hit by pin 48, thus tilting the lever 52 in a clockwise direction as seen in Figure 8 and operating the pawl 65 to cause it to engage and rotate the ratchet wheel 56 in a clockwise direction together with the shaft 57 on which the ratchet wheel 56 is keyed. On this shaft 57 intermediate the ratchet wheel 56 and the spur pinion 59 is mounted a driving pinion 72 keyed to the shaft 57 and the teeth of which pinion are in mesh with the teeth 36 of the boring bar 35.

Under the foregoing conditions of operation, so long as the pin 48 is held down for causing en-

gagement thereof with the lever 52, a feed movement of the pinion 72 (see Figure 7) will be imparted to the boring bar in a downward direction each time the lever 52 strikes the downwardly maintained pin 48. The greater the distance down the pin 48 is moved, as limited by ultimate full compression of spring 49, the greater will be the throw of the lever 52, and the downward movement of the bar 35. Thus the intermediate ratchet feed of the bar 35 for supplementing the gravitational and/or pressure fluid actuating feed actions of the auger may be resorted to at the will of the operator.

The foregoing description thus deals with the boring operation of my machine in three ways, viz, first, by boring operation incident to auger gravity feed; second, by use of the fluid pressure feed to supplement that of the gravity feed; and, third, by use of the intermittent ratchet feed to be employed with the gravity feed alone, or when availing of the gravity feed plus the pressure fluid operating feed, depending on the working conditions of resistance to boring operation.

The means for withdrawing the auger from the bored hole will now be set forth, of which certain parts have already been mentioned herein. Said means includes a rotating sleeve or hub 75 having a bearing race 76 with suitable anti-friction bearings between said race and bearing races 77 surrounding the lower portion of the carrier 37, the said rotating hub 75 being free to rotate independently of the carrier 37. On the upper end of the hub 75 is secured, by means of bolts, an idler gear 78 which is operative to function under certain conditions for effecting the withdrawal of the auger from the bore hole. Said idler reverse feed gear 78 has its bevel teeth in mesh with the corresponding teeth of the bevel gear 62 previously referred to as carried by the axis shaft 61 on the carrier. At the lower end of the rotating hub 75 said hub is formed with a brake drum 79 with which cooperates a normally expanded brake band 80 adapted to be tightened about the drum 79 by means of a hand lever 82 seen best in Figures 2 and 3, said lever being arranged externally of the boring head, carried thereby, having its handle located in a convenient manner to the operator's station which usually will be at one side of the boring head upon the ground adjacent to the machine.

When sufficient earth has been dug to reach the bottom of the hole, and while the auger is loaded, the operator will allow the auger to continue rotation, release the pressure feed action on the piston 46 and raise the lever 51 and trip pin 48, if either or both of the above feed instrumentalities are being used, and thereupon apply the brake 80 to the brake drum 79. This will cause the idler reverse feed gear 78 to be held stationary while the carrier assembly continues to revolve in the direction indicated by the arrow A in Figure 8. The reversing idler gear 78 now becomes a stationary circular rack on which the bevel end gear 62 will rotate in the direction of the arrow B as shown on Figure 9. The rotation of the gear 62 by turning gear 60 will cause the latter to rotate the gear 59 and therefore the shaft 57 and the rack feed gear 72 in the direction of the arrow C in Figure 9, thus causing the chain of gears just described to act so that the gear 72 will feed the boring bar 35 upwardly by reason of the meshing engagement of the teeth of the gear 72 with the teeth 36 on the boring bar 35. The upward feed operation of the boring bar incident to the action of the stationary re-

verse feed idler gear 78 will cause rapid withdrawal of the auger from the hole.

When the auger 20 clears the top of the hole, the load of dirt or other material carried thereby being no longer restrained sidewise by the wall of the hole, will ordinarily leave the auger by reason of centrifugal force. If, however, the soil or dirt on the auger is of a nature that causes it to stick to the auger instead of leaving the same by centrifugal action, the operator of the machine, by applying the disc brake 21, see Figure 5, may cause the rotation of the auger to suddenly stop, and the sudden stoppage will effectively dislodge the load brought upwardly from the hole by the auger. Of course, the application of the brake means 21 involves the automatic throwing out of the clutch means 10 in a manner previously described herein.

Reverting to the matter of the driving of the input shaft 5, it is noted again that earth boring units of the type of my invention are installed on various types of vehicles, and various types of power take-offs are employed. The power output shaft of a given vehicle transmission unit may revolve motorwise, while that of another unit may revolve counter motorwise. Since the auger 20 must revolve in the same direction, clockwise, regardless of the direction of the rotation of the power out-put shaft, the reversal of the position of the gear 26 as shown in Figure 3 to that shown in Figure 11, accommodates for the use of my invention with either motorwise or counter motorwise out-put power take-off shafts.

Under certain conditions it is desirable to feed the rack bar 35 upwards with maximum power effort, as when the auger 20 becomes hooked under an obstruction or is loaded to the extent that it cannot be raised in the usual manner by application of the brake 80. Under such conditions, the operator will reverse the direction of auger rotation by means of the vehicle transmission gearing from which the power take-off leading to the input shaft 5 is taken. In addition the carrier 37 will be operated in a direction reverse to that shown by the arrow A in Figure 8. Thereupon the trip pin 48 may be lowered and will strike the right hand side of the ratchet lever 52, shifting the latter at its upper end to the left as seen in Figure 8, and thereby causing the reverse acting pawl 55 to turn the ratchet wheel 56 in a direction opposite to the turning action which is produced by the operation of the pawl 65. Such action will of course result in rotation of the feed gear 72 coaxing with the teeth or rack 36 of the boring bar 35 to rotate in a manner to raise the boring bar instead of lowering it, as would be the normal operation of the feed action of the said feed gear 72.

From the foregoing it will be seen that I have produced a boring unit which has a wide range of flexibility of control and one which is designed to readily adapt itself as to adjustment for operation for digging under many different conditions of digging resistance. Since the operation of my boring unit will involve primarily the gravity feed of the auger and boring bar, a considerable amount of wear and tear incident to the use of special feed gearing is avoided since a large portion of such gearing may be dispensed with and such portion as is used does not have to be put into action except under difficult digging conditions.

A guide and bearing roller 85 works against

the side of the boring bar 35 opposite that engaged by the drive pinion 72, see Figure 7.

Having thus described my invention, what I claim as new and desire to secure by Letters Patent of the United States, is:

1. In an earth boring machine, a boring head, a rotating carrier therein, a boring bar mounted in the carrier for rotation therewith and for substantially non-retarded reciprocation therein whereby the weight of said bar in conjunction with an auger carried at the lower end thereof is capable of effecting a downward gravity feed, drive means for rotating said carrier, optionally operative means comprising a rack on said bar and a pinion on said carrier for supplementing said gravity feed, means for rotating said pinion comprising a ratchet wheel keyed thereto and pawl means for actuating said wheel, said ratchet wheel and pawl means being mounted on said carrier and rotative therewith, a motivating means mounted on said boring head and engageable with said pawl means by said rotation for intermittently driving said pawl means to actuate said ratchet wheel and said pinion to feed said bar downwardly.

2. In an earth boring machine, a boring head, a rotating carrier therein, a boring bar mounted in the carrier for rotation therewith and for substantially non-retarded reciprocation therein whereby the weight of said bar in conjunction with an auger carried at the lower end thereof is capable of effecting a downward gravity feed, drive means for rotating said carrier, optionally operative means comprising a rack on said bar and a pinion on said carrier for supplementing said gravity feed, means for rotating said pinion comprising a ratchet wheel keyed thereto and a pawl element engageable with said wheel, and pivotally secured to a lever having pivotal connection with said carrier, said lever thus revolving with said carrier about the axis thereof, said wheel and pawl element being mounted on said carrier, and rotative therewith, a motivating means comprising a plunger mounted on said boring head and engageable with said pawl element, said plunger being manually movable into the path of traverse of said lever for rocking the same about its pivot with each rotation of said carrier, to actuate said pawl element and said ratchet wheel and pinion to feed said bar downwardly.

3. In an earth boring machine, a boring head, a rotating carrier therein, a boring bar mounted in the carrier for rotation therewith and for substantially non-retarded reciprocation therein whereby the weight of said bar in conjunction with an auger carried at the lower end thereof is capable of effecting a downward gravity feed, drive means for rotating said carrier, optionally operative means comprising a rack on said bar and a pinion on said carrier for supplementing said gravity feed, means for rotating said pinion comprising a ratchet wheel keyed thereto and a pawl element engageable with said wheel, and pivotally secured to a lever having pivotal connection with said carrier, said lever thus revolving with said carrier about the axis thereof, said wheel and pawl element being mounted on said carrier, and rotative therewith, a motivating means comprising a plunger mounted on said boring head and engageable with said pawl element, said plunger being manually movable into the path of traverse of said lever for rocking the same about its pivot with each rotation of said carrier, to actuate said pawl ele-

ment and said ratchet wheel and pinion to feed said bar downwardly, and an additional pawl element engageable with said ratchet wheel at a diametrically disposed point with respect to said first pawl element, said additional pawl element being pivoted to said lever to a point which is oppositely disposed to the connection with said first pawl relative the pivotal connection between said lever and said carrier, for effecting reverse rotation of said ratchet wheel when the rotation of said carrier is reversed, said bar being raised thereby.

4. In an earth boring machine, a boring head, a rotating carrier therein, a boring bar mounted in the carrier for rotation therewith and for substantially non-retarded reciprocation therein whereby the weight of said bar in conjunction with an auger carried at the lower end thereof is capable of effecting a downward gravity feed, drive means for rotating said carrier, optionally operative means comprising a rack on said bar and a pinion on said carrier for supplementing said gravity feed, means for rotating said pinion comprising a ratchet wheel keyed thereto and a pair of pawl elements for actuating said wheel, said ratchet wheel and pawl elements being mounted on said carrier and rotative therewith, and a motivating means mounted on said boring head and engageable with one of said pawl elements by rotation in one direction of said carrier for intermittently driving one of said pawl elements to actuate said ratchet wheel and said pinion to feed said bar downwardly and engageable with the other of said pawl elements to raise said bar upon reverse rotation of said carrier.

5. In an earth boring machine, a boring head, a rotating carrier therein, a boring bar mounted in the carrier for rotation therewith and for substantially non-retarded reciprocation therein whereby the weight of said bar in conjunction with an auger carried at the lower end thereof is capable of effecting a downward gravity feed, drive means for rotating said carrier, optionally operative means comprising a rack on said bar and a pinion on said carrier for supplementing said gravity feed, means for rotating said pinion comprising a ratchet wheel keyed thereto and a pawl element engageable with said ratchet wheel and an actuator therefor mounted on said carrier for rotation therewith, and a motivating means mounted on said boring head and engageable with said pawl element by rotation for intermittently driving said pawl element to actuate said ratchet wheel and pinion to feed said bar downwardly, said motivating means comprising an element manually movable into the path of travel of said actuator to a selective degree for controlling the extent of movement thereof in actuating said pawl element.

6. In an earth boring machine, a boring head, a carrier rotatably mounted in said head, a boring bar mounted in said carrier and rotatable therewith and slideable therein, a rack on said bar, a feed pinion engaging said rack and mounted on said carrier, a first gear means rotatable as said pinion rotates, said pinion and gear means being normally idling and revolving with said boring bar about the axis of said carrier, a second gear means meshing with said first gear means and normally idling therewith, including brake means in the head for stopping rotation of said second gear means to effect a reaction for forcibly rotating said first gear

means, whereby said pinion is positively rotated for reciprocating said rack, and additional means for effecting rotation of said feed pinion, comprising a mechanism mounted on said carrier and rotative therewith but normally stationary with respect thereto and being connected to said pinion so as to be capable of effecting rotation thereof, including a manually controllable mechanism mounted on said boring head and being optionally engageable with said mechanism on said carrier to effect operation of said mechanism for positively rotating said feed pinion.

7. In an earth boring machine, a boring head, a carrier rotatably mounted in said head, a boring bar mounted in said carrier and rotatable therewith and slideable therein, a rack on said bar, a feed pinion engaging said rack and mounted on said carrier, a first gear means rotatable as said pinion rotates, said pinion and gear means being normally idling and revolving with said boring bar about the axis of said carrier, a second gear means meshing with said first gear means and normally idling therewith, means for mounting said second gear means comprising a bearing mounted axially within said carrier and supported thereby, a brake drum carried by said bearing, and a brake band surrounding said drum and carried by said boring head, including manual means carried by said boring head for actuating said brake drum for stopping rotation of said second gear means to effect a reaction for forcibly rotating said first gear means, whereby said pinion is positively rotated for reciprocating said rack.

8. In an earth boring machine, a boring head, a rotating carrier therein, a boring bar mounted in the carrier for rotation therewith and for substantially non-retarded reciprocation therein whereby the weight of said bar in conjunction with an auger carried at the lower end thereof is capable of effecting a downward gravity feed, including a drive means for rotating said carrier, and further including optionally operative means comprising a mechanism mounted on said carrier and rotative therewith but normally stationary with respect thereto, said mechanism being coupled to said pinion and capable of effecting rotation thereof, and a second mechanism mounted on said boring head and manually operative to engage said first mechanism intermittently as said carrier rotates, for driving said first mechanism to rotate said pinion and thus effect feeding of said bar, supplementing said gravity feed.

GEORGE H. CONNORS.
